SUCTION NOZZLE

Lars Ell, Stockholm, Sweden, assignor to Electrolux Corporation, Dover, Del., a corporation of Delaware

Application May 29, 1933, Serial No. 673,345
In Germany June 16, 1932

4 Claims. (Cl. 15—158)

My invention relates to the vacuum cleaner art and particularly to a suction nozzle intended to be used in conjunction with a vacuum cleaner unit.

More particularly, my invention contemplates a suction nozzle comprising two parts which may be readily secured together or separated. One of the parts comprises brush bristles adapted to surround the other part. The other part comprises a hollow resilient suction mouth piece. When the two parts are together they constitute a suction brush. When the part including the bristles is removed the resilient mouth piece may advantageously be separately used for cleaning.

The nature of my invention will be apparent from the following description considered in connection with the accompanying drawing, which forms a part of this specification and of which:

Fig. 1 is an elevational view showing my suction nozzle connected by means of a flexible hose with a vacuum cleaner unit; and

Fig. 2 is a view partially in cross-section, of the suction nozzle shown in Fig. 1.

Referring to the drawing, reference character 10 designates a vacuum cleaner unit which comprises a casing 11 mounted on suitable wheels 12 and enclosing suitable dust separating means and suction producing means. A flexible hose 13 is connected to the inlet 14 of the cleaner unit and to a rigid hollow handle member 15. The other end of handle 15 is secured to my improved suction nozzle, designated generally by reference character 16.

Nozzle 16 comprises a plate or base member 17 made of any suitable rigid material such as wood or metal. Plate member 17 is formed with a central aperture 18. Brush bristles 9 are secured in and extend downwardly from the lower face of member 17 adjacent to the periphery of the base member and around opening 18.

Reference character 19 designates a hollow member made of relatively soft resilient material, such as rubber. One end of member 19 is formed with a reinforced portion 8 which is adapted to receive and resiliently engage one end of hollow handle 15. The other end of member 19 is formed as part of a sphere 20, the lower portion being cut off, so to speak, to form a suction opening 21. The diameter of sphere 20 is greater than the diameter of aperture 18 in member 17. Member 19 is formed with a bead 22 spaced a short distance above the spherical portion 20 and the member is preferably formed so that the upper part, including reinforced portion 8 is at an

angle to the vertical when member 17 is horizontal.

In order to separate members 17 and 19, the spherical part 20 of the latter may be compressed, due to the resilient nature thereof, and withdrawn upwardly through the aperture 18. Likewise, when the two parts are to be placed together, spherical part 20 may be compressed and inserted into aperture 18. Member 17 is securely held on member 19 between the spherical portion 10 thereof and the bead 22.

In operation, when the two parts are placed together and connected, by means of the handle 15 and the hose 13, with the vacuum cleaner unit 10, and the latter is operated, air will be drawn in through the opening 21 and through the member 19, handle 15 and hose 13 to the dust separating member within the cleaner unit. If the cleaning member is passed over a surface to be cleaned with the bristles 9 in contact with the surface, the bristles will dislodge dirt adhering to the surface, which dirt will be picked up by the air drawn into opening 21 and carried with the air stream to the dust separating member 10. The part 20 is resilient and can be squeezed to adjust the size of the suction opening. It will be clear from what has been stated above that the base member 17 with the bristles 9 may be pulled off the member 19 and there is then provided a simple resilient nozzle.

The invention facilitates manufacture of this type of nozzle.

While I have shown and described a preferred embodiment of my invention, it is to be understood that this is for purposes of explanation only, and that the invention is to be limited only by the appended claims viewed in the light of the prior art.

What I claim is:

1. A suction nozzle comprising a base member 40 of rigid material formed with a central aperture, brush bristles secured to said base member and extending at right angles therefrom around said aperture, a hollow resilient member adapted to extend through said aperture and resiliently engage said base member, and an annular projection on said resilient member for positioning it with respect to said base member, said resilient member being formed with means for connecting it to a source of suction.

2. A suction nozzle comprising a base member of rigid material formed with a central aperture, brush bristles secured to said base member and extending at right angles therefrom around said aperture, a hollow resilient member adapt-

- ed to extend through said aperture and resiliently engage said base member, the portion of said resilient member extending through said base member adjacent to said bristles having a larger diameter than the rest of said resilient member and having a suction opening in the lower part thereof, and an annular projection on said resilient member spaced from the spherical portion, said base member being adapted to be held between said projection and said portion of larger diameter, said resilient member being formed with means for connecting it to a source of suction.
3. A suction nozzle comprising a base member of rigid material formed with a central aperture, brush bristles secured to said base member and extending at right angles therefrom around said aperture, a hollow resilient member adapted to extend through said aperture and resiliently engage said base member, the portion of said resilient member extending through said base mem-
- ber

ber adjacent to said bristles being formed as a part of a sphere and having a suction opening in the lower part thereof, and an annular projection on said resilient member spaced from the spherical portion, said base member being 5 adapted to be held between said annular projection and said spherical portion, said resilient member being formed with means for connecting it to a source of suction.

4. A suction nozzle comprising a tube of resilient material, the lower end of which has walls of substantially uniform thickness forming an enlargement, a brush member having a substantially rigid flat back fitted around said tube of resilient material and abutting said enlargement 10 to limit longitudinal movement of the back in one direction, said nozzle and back being further configured to prevent accidental longitudinal displacement of the back relative to the nozzle in the other direction.
